UNITED STATES PATENT OFFICE

91,232

DESIGN FOR A CANDY BOX

Albert Bonomo, Brooklyn, N. Y.

Application September 1, 1933. Serial No. 49,188

Term of patent 3½ years

To whom it may concern:

Be it known that I, ALBERT BONOMO, a citizen of the United States of America, residing at Brooklyn, in the county of Kings and State of New York, have invented a new, original, and ornamental Design for a Candy Box, of which the following is a specification, reference being had to the accompanying drawing, forming part thereof.

I claim:

The ornamental design for a candy box substantially as shown.

ALBERT BONOMO.
